PROTECTIVE WORKING GLOVE Egbert Michael-Lohs, Traunring 5, Traunreut, über
Traunstein, Germany

Filed Nov. 26, 1957, Ser. No. 699,086

Claims priority, application Germany Nov. 27, 1956

8 Claims. (Cl. 66—174)

The invention relates to a protective working glove intended especially for the metal-working industry, and in particular for grasping sharp-edged sheet-metal. For example, press operators are often exposed to the danger of considerably injuring the palm of the hand when removing sheet metal from punching machines. Hitherto, coarse leather gloves have been used for protective purposes, but these gloves have the disadvantage that, even after a short period of use, they may become unsuitable for further use in consequence of a single cut caused by sharp-edged sheet metal. These coarse leather gloves also have the defect that they make it difficult for the operator to feel the sheet metal and this hinders rapid and frictionless work.

The present invention provides a protective working glove consisting of a tube-like knitted glove which leaves the ends of the fingers and thumbs free and is knitted from spun synthetic fibre yarn and monofilament synthetic yarn in such manner that the monofilament yarn is positioned substantially on the outer surface of the glove, whereas the spun yarn is substantially on the inner side and constitutes a soft internal surface of the glove, since this yarn comprises a plurality of fine, smooth synthetic fibres. With the aid of this protective glove, the endangered portions of the hand are enclosed satisfactorily in a comfortable manner. The inner surface consisting of synthetic spun yarn (for example polyamide yarn) protects the hand against friction effects, whereas the extremely tough monofilament synthetic yarn (manufactured from a polyamide) on the outer side of the glove offers an extremely effective form of protection against cuts. Due to the fact that the end portions of the fingers and thumbs remain free, quicker and firmer grasping of the sheet metal by the operator is ensured, and this is essential for the speedy progress of the work in hand.

Further features of this protective working glove are described in detail hereinafter with reference to an embodiment illustrated in the accompanying drawings, wherein

Fig. 1 is a view of a protective glove;

Fig. 2 is a view of the protective glove of Fig. 1 positioned on the hand; and

Figs. 3 and 4 show the outer and inner sides, respectively of the knitted mesh of the protective glove.

As shown in Figs. 1 and 2, the protective working glove is knitted in the form of a roughly tubular portion 1 with a sleeve-like portion 2 to accommodate the thumb. As will be apparent from Fig. 2, this protective working glove is so designed that the ends 3 of the fingers and also the end 4 of the thumb remain free, so that rapid and secure grasping of sheet-metal or the like is made possible. Injury by sharp sheet-metal edges or the like is, however, effectively prevented by the glove. The glove is manufactured from a combination of synthetic spun yarn (spun from synthetic fibres) and synthetic monofilament yarn. The spun yarn and the monofilament yarn are knitted to form the protective glove in such

2

manner that, as shown in Figs. 3 and 4, the wire mesh 5 is positioned substantially on the outside of the glove, whereas the spun yarn indicated at 6 is positioned substantially on the inside of the glove, thus forming a soft, smooth internal surface which prevents friction. The hardly visible portions 5 of the monofilament yarn on the inside of the glove are so deeply embedded in the knitted fabric that they do not come into contact with the hand. On the other hand, it is apparent from Fig. 3 that the synthetic monofilament yarn 5 is placed substantially on the outside of the glove, so that it effectively protects the spun yarn 6 and also the hand against injury by cutting.

The new protective working glove is manufactured in known manner on twin-cylinder circular knitting machines. With the aid of a special arrangement of the thread guide, it is ensured that one of the materials, i.e., the spun yarn, is always on the inside, and the other material (synthetic wire) is always on the outside.

Advantageously, the glove "tube" 1 is, as shown in the drawing, made symmetrical about the centre line *a—a*, so that the thumb portion 2 is knitted on exactly in the centre of the "tube" 1. This special symmetric design has the advantage that the glove can be pulled over the hand from either side and that, furthermore, the glove can be worn both on the right and on the left hand. Thus there are four different ways of using the glove, so that the useful life of the glove is quadrupled as compared with conventionally designed protective gloves which can only be worn on one hand and in one position.

The glove "tube" 1 may be provided at both ends with an elastic knitted collar 7 of soft synthetic spun yarn, as shown in Figs. 1 and 2. The fingers and the wrist are enclosed in a pleasant and soft manner by these knitted collars.

I claim:

1. A protective working glove, comprising in combination, a tubular main portion having two open ends and formed with an opening intermediate said ends; and a tubular thumb portion having one end attached to the outside of said main portion in communication with said opening therein, and a free open end, said portions being of knitted construction and made of a spun yarn and a monofilament yarn in such a manner that the outer surface of said portions is predominantly formed by said monofilament yarn and the inner surface is predominantly formed by said spun yarn.

2. A protective working glove, comprising in combination, a tubular main portion having two open ends and formed with an opening intermediate said ends; and a tubular thumb portion having one end attached to the outside of said main portion in communication with said opening therein, and a free open end, said portions being of knitted construction and made of a spun yarn and a monofilament yarn in such a manner that the outer surface of said portions is substantially formed by said monofilament yarn and the inner surface is substantially formed by said spun yarn.

3. A protective working glove, comprising in combination, a tubular main portion having two open ends and formed with an opening intermediate said ends; and a tubular thumb portion having one end attached to the outside of said main portion in communication with said opening therein, and a free open end, said portions being of knitted construction and made of spun polyamide yarn and a monofilament polyamide yarn in such a manner that the outer surface of said portions is predominantly formed by said monofilament yarn and the inner surface is predominantly formed by said spun yarn.

4. A protective working glove, comprising in combination, a tubular main portion having two open ends and formed with an opening intermediate said ends; a tubular

thumb portion in communication with said opening therein, and a free open end, said portions being of knitted construction and made of a spun yarn and a monofilament yarn in such a manner that the outer surface of said portions is predominantly formed by said spun yarn; and an annular collar member attached to said main portion at one of said open ends thereof, said collar member being of knitted construction and made of spun yarn.

5. A protective working glove, comprising in combination, a tubular main portion having an axis and a plane of symmetry transverse to said axis, said main portion having two open ends and an opening intermediate said ends in said plane of symmetry; and a tubular thumb portion having one end attached to the outside of said main portion in communication with said opening therein, and a free open end, said portions being of knitted construction and made of a spun yarn and a monofilament yarn in such a manner that the outer surface of said portions is predominantly formed by said monofilament yarn and the inner surface is predominantly formed by said spun yarn.

6. A protective working glove, comprising in combination, a tubular main portion having two open ends and formed with an opening intermediate said ends; and a tubular thumb portion having one end attached to the outside of said main portion in communication with said opening therein, and a free open end, said portions being of knitted construction and made of a spun yarn and a monofilament yarn in such a manner that the outer surface of said portions is predominantly formed by said monofilament yarn and the inner surface is predominantly formed by said spun yarn, said spun yarn and said monofilament yarn being of the same type of material.

7. A protective working glove, comprising in combination, a tubular main portion having two open ends and

formed with an opening intermediate said ends; and a tubular thumb portion having one end attached to the outside of said main portion in communication with said opening therein, and a free open end, said portions being of knitted construction and made of a synthetic spun yarn and a synthetic monofilament yarn in such a manner that the outer surface of said portions is predominantly formed by said monofilament yarn and the inner surface is predominantly formed by said spun yarn.

8. A protective working glove, comprising in combination, a tubular main portion having two open ends and formed with an opening intermediate said ends; a tubular thumb portion having one end attached to the outside of said main portion in communication with said opening therein, and a free open end, said portions being of knitted construction and made of a synthetic spun yarn and synthetic monofilament yarn in such a manner that the outer surface of said portions is predominantly formed by said monofilament yarn and the inner surface is predominantly formed by said spun yarn; and an annular collar member attached to said main portion at one of said open ends thereof, said collar member being of knitted construction and made of synthetic spun yarn.
